US00D879754S

(12) **United States Design Patent** (10) **Patent No.:** **US D879,754 S**
(45) **Date of Patent:** **** Mar. 31, 2020**

(54) **PORTABLE ELECTRONIC DEVICE**

(71) Applicant: **HTC Corporation**, Taoyuan (TW)

(72) Inventors: **Chin-Wei Chou**, Taoyuan (TW);
Yi-Shen Wang, Taoyuan (TW);
Chien-Hsin Huang, Taoyuan (TW);
Meng-Sheng Chiang, Taoyuan (TW)

(73) Assignee: **HTC CORPORATION**, Taoyuan (TW)

(**) Term: **15 Years**

(21) Appl. No.: **29/589,994**

(22) Filed: **Jan. 6, 2017**

(51) LOC (12) Cl. **14-03**

(52) U.S. Cl.

USPC **D14/248**

(57) **CLAIM**

The ornamental design for a portable electronic device, as shown and described.

DESCRIPTION

FIG. 1 is a perspective view of a portable electronic device in accordance with our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The oblique line shading represents a reflective surface. The broken lines in the figures depict portions of the portable electronic device that form no part of the claimed design.

1 Claim, 6 Drawing Sheets
